(57) **CLAIM**

I claim the ornamental design for an electric bicycle switch button, as shown and described.

DESCRIPTION

FIG. 1 is a perspective view of an electric bicycle switch button showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front elevation view thereof, showing the electric bicycle switch button in use.

The broken lines in the drawings depict portions of the electric bicycle switch button that form no part of the claimed design.

1 Claim, 8 Drawing Sheets
